TEMPORARY BINDER

Filed June 16, 1922

UNITED STATES PATENT OFFICE.

HENRY C. MEYER, OF BELLEVILLE, NEW JERSEY.

TEMPORARY BINDER.

Application filed June 16, 1922. Serial No. 568,883.

To all whom it may concern:

Be it known that I, HENRY C. MEYER, a citizen of the United States, residing at Belleville, in the county of Essex and State 5 of New Jersey, have invented certain new and useful Improvements in Temporary Binders, of which the following is a specification.

This invention relates to a temporary binder, and an object of the invention is to provide a binder embodying principles which, altho particularly adapted for the temporary retention of magazines, pamphlets, and like periodicals, may as readily be 15 used as a binder for manifold pads, loose leaf pocket note books, and other similar articles.

A more detailed object is to provide a binder comprising a back part and opposite cover parts, and to provide the back part 20 with a simple improved gripping device adjustable to grip and securely hold the magazine, it being here noted that the term "magazine" is used hereinafter as a broad term comprehensive of any and all of the 25 various articles which may be held by this clamp device.

Other objects and aims of the invention, more or less specific than those referred to above, will be in part obvious and in part 30 pointed out in the course of the following description of the elements, combinations, arrangements of parts and applications of principles constituting the invention, and the scope of protection contemplated will be 35 indicated in the appended claims.

In the accompanying drawings which are to be taken as a part of this specification, and in which I have shown merely a preferred form of embodiment of the invention 40:

Figure 1 is a sectional view thru a binder constructed in accordance with this invention, the section being taken substantially upon the plane of line 1—1 of Fig. 2.

Figure 2 is an elevational view of the 45 structure seen in Fig. 1.

Figure 3 is an enlarged transverse sectional view similar to the upper portion of Fig. 1, but showing the gripping device in 50 released position, the gripping position being indicated by dotted lines, and

Figure 4 is an enlarged transverse detail section taken substantially upon the plane of line 4—4 of Fig. 1.

Referring to the drawings for describing 55 in detail the structure which is therein

shown, the reference character L indicates the back part of the binder, while the reference characters G and H indicate the opposite cover parts which are connected with 60 the back by hinge parts 5 so that the cover parts may be free to swing in the usual manner.

Both of these parts may be covered with 65 leather or other covering material, as indicated by the reference numeral 6, so that a proper and attractive exterior appearance is provided.

The back L is preferably formed with a 70 longitudinal groove 7 at its inner surface into which the binder portion of the magazine may be received so that said portion will be at all times held straight and firm. The back may be formed of any suitable 75 material, but is preferably fashioned from a strip of wood, or the like, and in forming the groove 7 opposite side wall portions 8 are provided which are intended to lap the 80 opposite surfaces of the magazine, as will be clearly apparent from inspection of Fig. 4.

At one end of the groove 7 is provided a 85 gripping member 9, while at the opposite end is a gripping member 10. Both of these gripping members are of substantially identical shape and size, and an essential feature of each is that it provides an inturned flange 90 part 11 shaped to provide comb teeth 12, the teeth of each member being directed toward the teeth of the other member and so spaced from the bottom wall of the groove 7 that they are adapted to engage between the leaves, or sheets, of the magazine.

The gripping member 9 is held rigid with 95 the back L as by means of screws, or the like, as 13, which extend thru the main portion of said member and into the material of the back.

The gripping member 10 is adjustable so 100 that it may be slid longitudinally of the back between the two extremes, as indicated by the full and dotted lines in Fig. 3. In order to accomplish this result the main, or body, portion, as 14, of the member 10 is provided with a longitudinally extending slot 15 thru which extends a headed pin 16 105 projecting from the back. The sliding movement of the member 10 is guided by engagement of said member with the opposite wall surfaces 17 of the groove 7, and the pin 16 serves merely to hold the member 110 against displacement and to limit its longitudinal movement.

Preferably a wear plate 18 is arranged beneath the member 10, being held by the pin 16 and by a second pin 19 spaced from the pin 16. The pin 19 may provide a but-
5 ton-shaped head 20 and the under surface of the portion 14 of the member 10 may be pro-
vided with a counter-sink 21 arranged to snap over the head 20 when the member 10 has been moved to gripping position, it
10 being understood that the portion 14 is re-
silient so as to effect the snap action when the parts are in proper position.

To use this device it is simply necessary to insert the binder portion of the magazine
15 into the groove 7 and slide it longitudinally along said slot until the comb of the gripping member 9 penetrates into the adjacent edge of the magazine, and then to slide the gripping member 10 inwardly so that
20 the comb 12 thereof will enter the opposite edge of the magazine.

To remove the magazine the member 10 may be withdrawn and the magazine there-
25 after disengaged from the member 9, or pref-
erably the magazine itself may be gripped and slid longitudinally along the slot in a direction toward the member 10, thereby forcing the member 10 outwardly and dis-
engaging the magazine from the member 9.
30 The magazine can then be drawn out of at-
tachment with the member 10.

It will be appreciated that the back L, and the gripping members, may be of any de-
35 sired width so that any number of maga-
zines, or any thickness of single magazine, can be held, also that the length of the binder portion of the different magazines may vary within appreciable limits without altering the effectiveness of this device.

40 The teeth 12 of the combs are preferably formed so that they are of uniform cross section thruout the greater portion of their length and are pointed at their ends only, substantially as indicated. By this means
45 the number of sheets, or pages, held between each two adjacent teeth is determined by the distance between the two teeth points, as indicated, for instance, X and Y in Fig. 2. As the comb enters the magazine this num-
50 ber of sheets is forced together, and thus provides a strong frictional grip between the opposing surfaces of the teeth and the surfaces of the group of sheets. This grip is effective as soon as the pointed portion of
55 the comb has entered and it will be apparent that the remainder of the length of the comb teeth provides essentially only against accidental disconnection and at the same time enables the use of the device upon mag-
60 azines having binder portions of different lengths.

As many changes could be made in this construction without departing from the scope of the invention as defined in the following claims, it is intended that all matter

contained in the above description or shown in the accompanying drawings, shall be interpreted as illustrative only and not in a limiting sense.

Having thus described my invention, what I claim as new and desire to secure by Letters Patent is:

1. A binder comprising a stiff back por-
tion having a longitudinally extending
groove therein adapted to receive the bind-
er part of a magazine and being of a length
at least as great as said binder part of the
magazine, a gripping member at one end of
the groove to grip the adjacent end of the
binder part of the magazine, a second grip-
ping member at the opposite end of the
groove to grip the opposite end of the bind-
er part of the magazine, said second grip-
ping member being separately formed and
being arranged to slide longitudinally in the
groove of the back portion, said second grip-
ping member consisting of an elongated
piece of sheet metal of a width to be re-
ceived between the side walls of the groove
so as to be guided by said side walls and
having a longitudinally extending slot
therethrough intermediate the side edges
thereof, and a retaining member fixedly
carried by the back portion projecting into
the groove and through said slot, adapted to
be engaged by the end walls of said slot to
limit the sliding movement of the gripping
member longitudinally along the groove,
and said retaining member having a head
thereon beyond the slot to engage the upper
surface of the gripping member to prevent
upward displacement of the gripping mem-
ber out of the groove, and thus retain the
gripping member in proper sliding engage-
ment within the groove.

2. A binder comprising a stiff back adapt-
ed to lie in engagement with the binder part
of a magazine, a gripping member at one
end of said back having a comb part ar-
ranged to enter between the leaves of the
magazine, a second gripping member at the
opposite end of the back comprising a plate
of resilient sheet metal disposed flat upon
said back having a portion bent upwardly
therefrom provided with comb teeth extend-
ing over the plate adapted to enter between
the leaves of the magazine, a retaining mem-
ber fixed to the back and projecting through
a longitudinally extending slot of the plate
and having a head thereon to retain the
plate against lifting from the back while
permitting limited longitudinal sliding
movement of the plate, and snap acting
means interengaging between the back and
the plate utilizing the resiliency of the plate
resisted by the head of the retaining mem-
ber to hold the plate in gripping position.

In testimony whereof I affix my signature.

HENRY C. MEYER.
